UNITED STATES PATENT OFFICE.

WILLIAM KOEHLER, OF FULTON, NEW YORK, ASSIGNOR TO AMERICAN TEXTILE SPECIALTY MACHINERY COMPANY, OF NEW YORK, N. Y., A CORPORATION OF NEW YORK.

SHUTTLE-SPINDLE.

No. 849,073.

Specification of Letters Patent.

Patented April 2, 1907.

Application filed August 25, 1905. Serial No. 275,718.

To all whom it may concern:

Be it known that I, WILLIAM KOEHLER, a citizen of the United States, residing at Fulton, in the county of Oswego and State 5 of New York, have invented certain new and useful Improvements in Shuttle-Spindles, of which the following is a specification.

This invention aims to provide an improvement in spindles, whereby the quills or bobbins or cop-tubes are easily applied upon the spindle and easily withdrawn therefrom, but are retained thereon very firmly, so as to avoid displacement under the shocks which result from the throwing of the shuttle back and forth. For this purpose a screw-thread of very slight pitch is provided on a suitable portion of the spindle, the pitch being so slight as to lock the cop-tube or the like against longitudinal movement in the direction of the spindle, and therefore to lock it against displacement by the shocks which it sustains in the throwing of the shuttle. At the same time this construction permits of very easily removing the tube by first giving it a very slight unscrewing motion. The effectiveness of the threads to bite into the paper or other material of the tube is increased by one or more grooves running longitudinally of the spindle, and forming, where such groove crosses each of the screw-threads, a point of metal, which readily enters the material of the tube, so as to cut spiral threads on the inner face of the tube, and forming a firm lock between the tube and the spindle.

The accompanying drawings illustrate embodiments of the invention.

Figure 1 is an elevation of a solid steel spindle. Fig. 2 is an elevation, partly in section, of a split spindle. Fig. 3 is an elevation of the spindle of Fig. 2 looking in a direction at right angles to that of Fig. 2. Fig. 4 is a cross - section on the line 4-4 of Fig. 1.

Referring to the embodiments of the invention illustrated and first to Fig. 1, A is a solid steel spindle tapered as usual. Upon any desired portion of said spindle there is cut a screw-thread B of very slight pitch, so as to run approximately at right angles to the spindle and to practically lock the tube against yielding to longitudinal shocks.

Ordinarily it will only be found necessary to run the thread B over a comparatively short portion of the spindle, as shown, since each thread holds the tube with considerable force. The cop, with the usual interior paper tube, is applied to the spindle in the ordinary manner by shoving it hard over the tapered end. Ordinarily the friction of its engagement with the spindle is depended upon to hold it in place. In the present case, however, after it is shoved down upon the spindle it is given a partial turn—say a half-turn to the right—(supposing a right-hand thread be used.) By this additional twist the comparatively sharp threads B engage the inner surface of the tube sufficiently to force it more tightly down toward the heel of the spindle and at the same time, which is very important, to form internal threads in the tube in engagement with the threads B. The engagement between the two sets of threads is then nearly normal to the length of the spindle and holds the tube on the spindle, even in broad looms of the highest speed. It is even difficult to withdraw the empty tube by pulling it longitudinally; but by giving it a short turn to the left the screw-threads force it toward the smaller end of the spindle and permit its ready withdrawal. The wear upon the inner surface of the tube is comparatively slight, and even paper tubes may be used on these spindles from ten to fifty times. The elasticity of the tube and the sharp edge of the thread are depended upon to force the material into the screw-threads B, and the very least elasticity is sufficient for the purpose. The threads are preferably cut flush with the smooth tapered surface of the spindle, or even minutely below such surface. They should be at most flush therewith, so as to oppose no obstruction to the longitudinal thrusting of the tube upon the spindle. In the further rotation and slight advancement the sharp edges of the teeth engage the cop sufficiently to cut into the same and hold it firmly. I have found by experiment that the engagement of the threads with the tube is effected more readily and more deeply by providing one or more grooves C, (preferably longitudinal,) which intersect the screw-threads and leave substantially triangular projecting points,

such as D, which cut or chisel a deep thread into the inner surface of the tube from the beginning of the twisting movement. These longitudinal grooves by breaking the continuity of the threads also prevent the tube from unscrewing as readily as would be the case with a smooth continuous thread. Thus they add to the locking effect of the slight pitch of the threads, and they permit the use of threads of greater pitch, if that were desirable for any other reasons.

The principle of this invention may be very conveniently applied to split spindles, either solid or hollow. The latter type is illustrated in Fig. 2, the thread being there shown as applied to the sheet-steel spindle of Patent No. 790,611, May 23, 1905, to Bell. Here the spindle is made of two halves E and F, pressed out of sheet-steel, and either made of spring metal themselves or provided with an interposed spring, so that they tend to separate to provide a space G between them. It is usual to automatically press the two halves E and F together when a tube is to be applied thereto. Nevertheless the space G serves to an extent as the equivalent of the grooves C of Fig. 1 in producing sharp points D on the threads B, which enable them to more readily enter the material of the tube and in roughening the threads, so as to prevent too easy unscrewing of the tube. At the same time it is preferred not to depend on the space G alone for this purpose, but to provide also grooves C at the centers of the halves E and F, as shown in Fig. 3.

The invention is of particular importance when applied to this type of spindle because of the facility with which the thread can be formed. The half-thread on each of the two members E and F may be, in fact, stamped in the metal by the same operation which stamps the half-cone shape, and the groove C may also be formed in the same operation.

Though I have described with great particularity of detail certain specific embodiments of my invention, yet it is not to be understood therefrom that the invention is limited to the particular embodiments disclosed. Various modifications thereof in detail and in the arrangement and combination of the parts may be made by those skilled in the art without departure from the invention.

What I claim is—

1. A shuttle-spindle having a smooth tapered surface over the principal part of its length and provided over a portion of its length with a screw-thread having a sharp edge adapted to readily cut into a cop-tube. 55

2. A shuttle-spindle provided over a portion of its length with a screw-thread having a sharp edge adapted to readily cut into a cop-tube and of such slight pitch as to lock the tube in engagement with said thread against longitudinal movement, said spindle having a smooth tapered surface projected 65 outward at least as far as the outer edge of said threaded portion.

3. A shuttle-spindle provided with transverse threads having a sharp edge adapted to readily cut into a tube, and a longitudinal 70 groove interrupting said screw-thread and forming sharp points for said threads.

4. A shuttle-spindle provided over a portion of its length with a screw-thread having a sharp edge adapted to readily cut into a 75 cop-tube and of such slight pitch as to be at approximately a right angle to the axis of the spindle and to lock the tube in engagement with said thread against longitudinal movement, a longitudinal groove being extended 80 across said thread.

5. A shuttle-spindle composed of hollow segmental portions, and having a screw-thread formed thereon with a sharp edge adapted to readily cut into a cop-tube and of 85 such slight pitch as to lock the tube in engagement with said thread against longitudinal movement.

6. A shuttle-spindle composed of hollow segmental portions, and having a screw-thread formed thereon with a sharp edge adapted to readily cut into a cop-tube and of such slight pitch as to lock the tube in engagement with said thread against longitudinal movement, and a groove interrupting 95 said screw-thread and forming sharp points to readily enter the material of the tube.

In witness whereof I have hereunto signed my name in the presence of two subscribing witnesses.

WILLIAM KOEHLER.
